The ornamental design for a lid for a freight box, as shown and described.

DESCRIPTION

FIG. 1 is a top perspective view of a lid for a freight box, showing my new design;

FIG. 2 is a bottom perspective view thereof;

FIG. 3 is a side elevational view thereof, the side opposite that shown in FIG. 3 being identical thereto; and, FIG. 4 is a front elevational view thereof, the side opposite that shown in FIG. 4 being identical thereof.

FIG. 3

FIG. 4
